UNITED STATES PATENT OFFICE.

PETER J. JOECKEN, OF CLEVELAND, OHIO, ASSIGNOR TO THE AMERICAN
WASHBOARD COMPANY, OF SAME PLACE.

WASHBOARD.

SPECIFICATION forming part of Letters Patent No. 671,801, dated April 9, 1901.

Application filed November 9, 1900. Serial No. 35,899. (No model.)

To all whom it may concern:

Be it known that I, PETER J. JOECKEN, a citizen of the United States, residing at Cleveland, in the county of Cuyahoga and State of Ohio, have invented or discovered certain new and useful Improvements in Washboards, of which improvements the following is a specification.

The invention described herein relates to certain improvements in washboards, and has for its object a construction whereby the warping and buckling of the backboard and the outward bowing of the legs or side pieces due to the swelling and shrinking of the same are prevented and whereby a more firm and rigid support for the rubbing-face is provided.

The invention is hereinafter more fully described and claimed.

20 In the accompanying drawings, forming a part of this specification, Figure 1 is a view, partly in front elevation and partly in section, of my improved washboard. Fig. 2 is a vertical transverse section of a double-faced washboard embodying my improvement, and Fig. 3 is a similar view of a single-faced wash-

35 board. In the practice of my invention the side bars 1, headpiece 2, brand-board 3, and rubbing face or faces 4 are constructed in the usual or any suitable manner. The backboard 5 consists of a series of two or more sections supported and spaced by a series of three or more cross-pieces 6. The end cross-pieces are similar to those now used in washboards and have the ends of the rubbing-faces secured thereto. The intermediate cross piece or pieces alternate with the sections of the backboard and serve as rests or supports 40 for the adjacent upper section of the backboard. The ends of the backboard-sections project into grooves in the inner faces of the side bars, and the middle portions of the sections are held in line with the intermediate cross-piece by the rubbing-faces of double-faced boards or by the rubbing-face and ribs 7 on the cross-pieces 6^a in single-faced washboards.

45 As in use the backboard or backboard-sections would rest on the lower cross-piece, the

gap or opening left for expansion or swelling would be between the upper end of the backboard and the upper cross-piece were it not for the interposition of the intermediate cross-pieces. By the employment of the intermediate cross-piece the gap or opening for expansion or swelling is divided, as clearly shown in the drawings, part of such gap being between the upper cross-piece and the upper section of the backboard and part between the intermediate cross-piece and the lower section of the backboard, and, further, the intermediate cross-piece, having its ends nailed or otherwise secured to the legs or side pieces, serves to prevent the outward bowing of the legs or side pieces as would permit of the dropping out of the backboard and rubbing-face.

The cost of lumber increases nearly in direct proportion to increase in width. Hence by making the backboard of a series of comparatively narrow pieces in lieu of one broad piece a very considerable saving in expense of material is effected.

55 As the ends of the intermediate cross-piece are attached to the side bars by nails or other suitable means, a very rigid frame is formed.

60 I claim herein as my invention—

1. A washboard provided with a backboard formed in horizontal sections, and a cross-piece intermediate of adjacent backboard-sections, said cross-piece having its ends secured to the side bars or legs, and serving to support the sections in vertical position and to prevent twisting or bowing of the legs, substantially as set forth.

65 2. A washboard provided with a backboard formed in sections and with cross-pieces having supporting-ribs and arranged at the ends and intermediate of the backboard-sections, the cross-pieces having their ends secured to the side bars or legs of the washboard, substantially as set forth.

70 In testimony whereof I have hereunto set my hand.

PETER J. JOECKEN.
